UNITED STATES PATENT OFFICE.

JOHN S. RATHBONE, OF MYSTIC, CONNECTICUT.

DESIGN FOR A SPOON.

SPECIFICATION forming part of Design No. 22,031, dated December 6, 1892.

Application filed October 22, 1892. Serial No. 449,704. Term of patent 7 years.

To all whom it may concern:

Be it known that I, JOHN S. RATHBONE, of Mystic, in the county of New London and State of Connecticut, have invented and produced a new and original Design for a Spoon, of which the following is a specification.

Reference is to be had to the accompanying drawings, forming a part of this specification, in which similar letters of reference indicate corresponding parts in both figures.

Figure 1 is a front view of a spoon having my design, and Fig. 2 is a back view of the same.

The leading feature of my design consists of the representation of a bunch of a plant known as "golden-rod," the stems A of the

bunch extending along the handle of the spoon and the flowers B forming a wreath on the enlarged upper end of the said handle. The wreath incloses on one side of the spoon a bust-like figure C and on the back a shield D, as is plainly illustrated in the drawings.

The bowl of the spoon is formed of and representing an eagle E. A band or like figure F winds around the stems A.

I claim—

The design for a spoon, as herein shown and described.

JOHN S. RATHBONE.
